UNITED STATES PATENT OFFICE.

ALEXANDER FRANCIS GARDEN BROWN, OF DALRY, SCOTLAND.

ROTARY ENGINE, PUMP, AND BLOWER.

SPECIFICATION forming part of Letters Patent No. 507,780, dated October 31, 1893.

Application filed October 12, 1892. Serial No. 448,707. (No model.) Patented in England July 14, 1892, No. 12,915.

To all whom it may concern:

Be it known that I, ALEXANDER FRANCIS GARDEN BROWN, gentleman, a citizen of the United Kingdom of Great Britain and Ireland, residing at Swindridge Muir, Dalry, in the county of Ayr, Scotland, have invented new and useful Improvements in Rotary Engines, Pumps, and Blowers, (which have been patented in Great Britain by Letters Patent, dated July 14, 1892, No. 12,915;) and I do hereby declare that the following is a full, clear, and exact description of the invention, which will enable others skilled in the art or manufacture to which it relates to make and use the same.

In the drawings, Figure 1, is a transverse vertical section; Fig. 2, a longitudinal section. Fig. 3, is a view similar to Fig. 1, of an engine having two or more abutments. Fig. 4, is a view of the pistons adapted to the form of engine shown in Fig. 3; Fig. 5, a view similar to Fig. 1, of a modification.

Under one modification of the improved engine represented in Figs. 1 and 2 the piston A is preferably of eccentric form and the abutment is composed of an oscillating arm or door B centered in a recess C in the cylinder casing D but instead of bearing directly on the periphery of the piston as is usual the said abutment has near its free end a segmental piece B' pivoted or fitted to oscillate in a seat B² formed in it the said segment B' bearing on and being rocked by the motion of the piston A. Steam or other fluid is admitted to a chamber C' formed at the back of the abutment arm or door B and passes through a port b therein and through a port b' in the pivot on which the segment oscillates when the latter port b' is brought in line with the first port b by the motion of the segment due to the travel of the piston A the oscillating segment thus acting as a steam admission valve; and from the ports b, b' the steam enters the cylinder D in front of the oscillating segment B' and impels the piston in the direction indicated by the arrow. By the travel of the piston A the motion imparted to the segment B' is such as to completely open the ports b, b' and close them during each revolution, steam being admitted on one side and being exhausted on the opposite side of the segment the exhaust taking place through a

port b² in the pivot of the oscillating abutment B. In this arrangement steam is admitted once for each revolution of the engine and may be cut off at any part of the revolution, but two or more abutment arms constructed as above described may be fitted at intervals around the cylinder in which case steam may be admitted twice or oftener during each rotation.

The engine is made reversible by duplicating the abutment arm or arms and valve arrangements and cutting off the steam supply from the one valve while the other receives steam. The steam may also be expanded through a series of cylinders on the same or on separate shafts or as indicated diagrammatically at Figs. 3 and 4 a single cylinder D may be employed and fitted with a multiple throw piston A, A', A², abutment arms provided with the distributing valve arrangements above described being provided for each piston and fitted to each of the compartments into which the cylinder D is divided by disks F formed between the several portions of the multiple throw pistons A, A', A².

The shaft E carrying the piston or pistons where it passes through the ends of the cylinder D is packed steam tight by a sleeve G contained within a gland G' both sleeve and gland having in their lengths two different diameters, a soft metal, asbestos or other packing ring H being inserted where the greater diameter of the sleeve meets the part of lesser diameter of the gland. The inner end of the sleeve G which is of the lesser diameter abuts against the piston A or that part of the shaft E carrying the piston and which is of greater diameter than the part passing through the sleeve G and around the said inner end a ring I is so placed that it bears upon the end of the piston A against which it is maintained steam tight by a series of spiral or other springs J let into the inner end of the gland G'.

In another modification of the engine represented in transverse vertical section at Fig. 5 the abutment or abutments is or are made in the form of one or more pistons or plungers B having a reciprocating motion in a chamber C extending radially from the top or side of the cylinder D and having formed at its or their inner end or ends a pivot seat

B² for an oscillating segment B' bearing on the periphery of the piston A and oscillated thereby. The radial piston or plunger B is hollow and is divided by a web or partition B³ on one side of which steam is admitted through a port and passage b, b' extending through the plunger and the pivot on which the segment oscillates and thence the steam enters the cylinder to impel forward the piston A. On the opposite side of the segment the exhaust steam escapes by a second port b² in the pivot piece of the segment B' and through a port b³ into the hollow plunger B on the side of the web opposite that on which the live steam enters, the parts being so arranged that the steam and exhaust passages are opened and closed at the proper times by the action of the engine piston A on the oscillating segment B'. In this modification which is also adapted to be compounded or operated as a multiple expansion engine in the manner described with reference to Figs. 3 and 4 or by the use of a series of cylinders, reversal of the engine is effected either by duplicating the abutment B or by admitting the steam by the exhaust passage b² b³ and exhausting through the steam inlet b b'.

Both the abutment B of Fig. 1 with its segment B' and the segment B' of Fig. 6, may be termed an oscillating valve device as in both cases the inlet and outlet of steam is controlled thereby, and both devices taken as a whole have features common to both in that the inlet is on one side of the center of the oscillating device while the outlet is on the other side of said center.

Having now described my invention, what I desire to claim and secure by Letters Patent is—

1. In combination, the cylinder, the rotary piston therein the oscillating segment bearing on the piston to be operated thereby to control the admission of steam from the supply, and the oscillating abutment to oscillate with the said segment, substantially as described.

2. In combination, the cylinder and casing having the inlet and outlet arranged adjacent to each other, the rotary piston in the cylinder and the oscillating valve device having at one side of its center an inlet port leading to one side of the cylinder and piston from the inlet of the casing and on the other side of its center an outlet port leading from the other side of the cylinder and piston to the outlet port, said oscillating device having swinging movement in the direction of the piston's rotation and supported to have an additional movement to and from the center of the cylinder, substantially as described.

3. In a rotary engine, pump or blower the combination of a series of pistons rotating within a cylinder and set one in advance of another and a corresponding series of abutments each carrying an oscillating segment bearing on one of the pistons and operated thereby to automatically open and close steam and exhaust ports formed in the abutment and segment substantially as described.

In witness whereof I have hereunto set my hand and seal this 17th day of August, 1892.

ALEXANDER FRANCIS GARDEN BROWN. [L. S.]
